United States Patent

Des. 237,999
Patented Dec. 9, 1975

237,999

WARNING DEVICE FOR EMERGENCY VEHICLES OR THE LIKE

Richard C. Runyon, Los Angeles, Calif., assignor to
Royal Industries

Filed Jan. 16, 1975, Ser. No. 541,583

Term of patent 14 years

Int. Cl. D10—06; D26—06

U.S. Cl. D48—32 R

Fig. 1

Fig. 2

FIG. 1 is a front elevational view of a warning device for emergency vehicles or the like showing my new design;

FIG. 2 is a top plan view thereof;

FIG. 3 is a rear elevational view thereof;

FIG. 4 is a bottom plan view thereof;

FIG. 5 is a left end elevational view thereof; and

FIG. 6 is a right end elevational view thereof.

The perforations on the siren in FIGS. 1, 2 and 3 are partially shown for convenience of illustration, it being understood that the perforations are continuous over the areas indicated. The indicia is shown in broken lines in FIG. 3 for illustrative purposes only.

I claim:

The ornamental design for a warning device for emergency vehicles or the like, substantially as shown and described.
